No. 824,205.

PATENTED JUNE 26, 1906.

W. E. PORTER.
INTERMITTENT ALARM CLOCK.
APPLICATION FILED JAN. 8, 1906.

UNITED STATES PATENT OFFICE.

WILSON E. PORTER, OF NEW HAVEN, CONNECTICUT, ASSIGNOR TO NEW HAVEN CLOCK CO., OF NEW HAVEN, CONNECTICUT, A CORPORATION.

INTERMITTENT-ALARM CLOCK.

No. 824,205.

Specification of Letters Patent.

Patented June 26, 1906.

Application filed January 8, 1906. Serial No. 295,065.

To all whom it may concern:

Be it known that I, WILSON E. PORTER, a citizen of the United States, residing at New Haven, in the county of New Haven and 5 State of Connecticut, have invented a new and useful Improvement in Intermittent-Alarm Clocks; and I do hereby declare the following, when taken in connection with the accompanying drawings and the figures of 10 reference marked thereon, to be a full, clear, and exact description of the same, and which said drawings constitute part of this specification, and represent, in—

Figure 1, a partial view of my improved 15 intermittent-alarm clock with its rear movement-plate removed; Fig. 2, a broken view, in vertical section, on the line *a b* of Fig. 1, showing in particular the verge-arbor, the arm depending therefrom, the vibratory spring 20 carried by the said arm, and the alarm-wheel; 25 Fig. 3, a perspective view of the carrier-arm and vibratory spring.

My invention relates to an improvement in 25 intermittent-alarm clocks of the type shown and described in my prior patent, No. 580,056, dated April 6, 1897, the object being to produce a simple, reliable, and durable alarm mechanism composed of few parts and assisting rather than handicapping the 30 time-train during the period when the alarm is being intermittently sounded.

With these ends in view my invention consists in an intermittent-alarm clock having certain details of construction and combinations of parts, as will be hereinafter described, and pointed out in the claims.

In carrying out my invention as herein shown I provide the verge-arbor 2 of the alarm-train with a depending carrier-arm 3, 40 made, as shown, of sheet metal and having its lower end bent forward at a right angle to form a seat 4 for the attachment, by a screw 5 or other means, of the inner end of a thin flexible vibratory stop-spring 6, free at its 45 outer end, arranged in a horizontal plane and having a long slot 7 for the reception of the teeth of a star-like intermittent-alarm wheel 8, interposed between two collars 9 on a special alarm-arbor 10, journaled at its ends 50 in the front and rear movement-plates 11 and 12 and carrying a lantern-pinion 13, meshed into by the third wheel 14 of the time-train. The said arbor 10 corresponds, in effect, to the seconds-hand arbor of a time-train and may be used for a seconds-hand, if desired. The third wheel 14 of the time-train is driven by the second wheel 15, in turn driven by the main wheel 16, concentric with the mainspring 17. The said verge-arbor 2 carries the verge 18, the hammer 19, and the stop-wire 20, the verge 18 coacting with an escapement-wheel 21, the arbor 22 of which carries a pinion 23 and the stop-wire coacting with an alarm let-off spring 20^a, operated in the usual manner, as 65 shown in my said prior patent. The said pinion 23 is meshed into by the alarm main wheel 24, which is driven by an alarm-spring 25, encircling the stem-winding arbor 26. As to the time and alarm trains they may be of 70 ordinary and well-known construction and do not require detailed illustration or description.

When the alarm mechanism has been let off in the usual manner by the release of the 75 stop-wire 20 by the let-off spring 20^a, the power of the alarm-spring 25 will be transmitted through the alarm-train to the stop-spring 6, which will be pulled from left to right, with the effect of assisting in turning 80 the alarm-wheel 8 in the direction in which it is being turned by the mainspring 17 through the medium of the time-train. In other words, from the moment the alarm-train is let off in the usual way the power of the 85 alarm-spring will be thrown open upon the alarm-wheel, 8 so that the alarm-train will assist rather than handicap the action of the time-train. If at the time the alarm-train is let off the end wall 7^a of the slot 7 of the 90 spring 6 is engaged with one of the teeth of the alarm-wheel 8, the alarm-train will not be released for the sounding of the alarm until the wheel 8 has revolved sufficiently to release the spring 6. When that takes place, 95 the alarm-train will be released and the alarm will be sounded by the rapid oscillation of the arbor 2, which as it oscillates will vibrate the spring 6 rapidly back and forth underneath the wheel 8 until the same has brought one of its teeth in position to catch the spring by its end wall 7^a. The alarm-train will then be restrained until the wheel 8 has been sufficiently rotated to again release the spring 6, which will then vibrate until it is caught by a 105 tooth of the wheel, and so on.

It is apparent that in carrying out my invention some changes from the construction herein shown and described may be made. I would therefore have it understood that I do not limit myself thereto, but hold myself at liberty to make such departures therefrom as fairly fall within the spirit and scope of my invention.

I claim—

- 10 1. In an intermittent - alarm clock, the combination with the time and alarm trains thereof, of an alarm-wheel driven by the time-train, and a vibrating spring connected with the alarm-train and engaging with the teeth of the said wheel which it tends to revolve in the direction in which the wheel is revolved by the time-train.
- 15 2. In an intermittent - alarm clock, the

combination with the time and alarm trains thereof, of an arm depending from the verge-arbor of the alarm-train, a flexible spring secured to the said arm and formed with a longitudinal slot, and an alarm-wheel driven by the time-train and having its teeth entered into the seat of the said spring which, as it turns, releases the said spring which then vibrates as the alarm sounds until it reengages with another tooth of the wheel.

In testimony whereof I have signed this specification in the presence of two subscribing witnesses.

WILSON E. PORTER.
